UNITED STATES PATENT OFFICE.

BENJAMIN C. KING, OF BROOKLYN, NEW YORK.

EXTERNALLY-OPERATED CURRENT-CONTROLLING DEVICE.

Application filed June 25, 1924. Serial No. 722,418.

To all whom it may concern:

Be it known that I, BENJAMIN C. KING, a citizen of the United States, and resident of Brooklyn, in the county of Kings and State of New York, have invented a certain new and useful Externally-Operated Current-Controlling Device, of which the following is a specification, the same being a full, clear, and exact description of the invention, its structure, and operation.

This invention relates to electric devices which are installed in buildings for effecting the connection between the service-mains and the distributing wires, and provided with switching devices for controlling the current, and also with safety means for protecting the service-wires from destructive currents.

The present invention has for its object to provide a protective casing or housing for the exposed switches and wires, the casing being either of conducting or non-conducting material as desired.

In a construction like the present one wherein the heavily charged conductors and switches are of the exposed type the hand of the operator would be liable to contact with some exposed portions if the cover of the housing could be raised while the parts were so charged. Again in switch boxes where the switches are operated by an overhead actuating means, damage is apt to occur by the accidental contact of a conductive piece of material with the exposed conductors. I obviate this danger by providing means whereby the charged rupturing, opening or breaking ends of the switch contact members—which are spaced a good distance apart—are always higher from the base than the switch actuating means, which latter work at all times below the said contact members, whereby the liabilities to injury enumerated above are eliminated and greater safety in operating the device is secured.

Another object of the invention is to provide manually actuated safety means to control the electric current supply from the entrance of the service-wires to the load.

Another object of the invention is the provision of means to prevent access to the controlling devices by employing a locking device operating in connection and in conjunction with externally operated means.

Another object of the invention is the provision of means to control the current

which means is supported and held in operative position by means of an insulating base.

Another object of the invention is to provide insulating means to hold the current carrying devices apart and in position to be operated at all times.

A still further object of the invention is to provide a device of the class described which shall be of high contact efficiency, simple in construction, and efficient and durable in practical operation, it being understood that while I have shown for illustration some forms of switches which may be advantageously used, yet it is evident that the invention may be incorporated in and used in connection with any other form of switching devices and actuating and protecting means therefor, and with any other form of circuit.

With the above named objects, and other objects and purposes, which will be described below, in view, the invention consists in the construction, arrangement, combination and operation of parts hereinafter set forth.

In the drawings, illustrative of one embodiment of the invention, which accompany and form a part of this specification—

Figure 1 represents an elevation looking into the box with the cover hanging down;

Figure 2 is a partial view of the casing showing the orifice therein;

Figure 3 is a partial elevation partly broken away to show the engagement of the yoke and hook on the cover;

Figure 4 is a section of the box illustrating the groove in the base;

Figure 5 is a partial elevation partly broken away to show the yoke when released from the cover and in open position;

Figure 6 is a partial plan view illustrating the insulating bar and connection; and Figure 7 is an elevation of the structure shown in Figure 6.

Referring more in detail to the drawings, the numeral 1 denotes a connection block of proper dimensions and made of refractory insulating material which is preferably enclosed in a protecting casing or housing 2 of suitable material and size which serves to form a foundation or support for the block or base as well as affording a protective covering for the same, which casing is ordinarily formed with rear and side walls and provided with a closure means for

the front thereof, as a hinged cover 3. Suitable means may be employed to fix the base to the protecting and enclosing housing in the ordinary manner.

5 The base 1 is preferably formed with a supporting longitudinal groove 4 extending approximately along the centre of the bottom of the base and serving to enclose and form a guide and bearing for the actuating means of the current controlling device, which groove meets and terminates in a preferably transverse slot 5 in which one arm of the said actuating device works as and in the manner hereinafter described.

15 The base may support contacts as ordinary binding posts or contacts adapted for attachment with clips, or both. The contacts used by me in the present embodiment comprise contacts 6, 7 and 8 connected by a terminal strip 9 carrying a fuse 10, contact 11, connection members 12, circuit controlling members or switch levers 13, connecting members 14 and contacts 15; and, on the opposite side of the block, contacts 21, 22 and 25 23, connecting members 17, circuit controlling member or switch lever 18, connecting members 19 and contacts 20; at least some of the said contacts being made so as to constitute connecting or coupling devices 30 adapted to be used as co-operating clip contacts in the usual way.

To the contact or connection members 12 and 17 are attached the control members 13 and 18 in a hinging and supporting relation, while the opposite rupturing or circuit opening ends of said pair of control members are adapted to form co-operative members to coat at will with the contact or connection members 14 and 19 in order to make 40 and break a circuit.

By the use of the said standard contacts I am enabled to adapt my invention for use with any of the standard electric service and distributing arrangements, or with such 45 combinations of circuits as may be desired, one example of the same being indicated by dotted lines in the drawings.

50 My said protective housing for the circuit connecting parts serves to prevent tampering with the same or displacement of the parts thereof, and it is also conveniently used as a support for the base carrying the switch actuating means, which latter may be operated in the following manner:—The 55 pair of control members 13 and 18 are connected by an insulating bar 26 preferably passed through the same and carrying a depending lip 27 fixed to the same, the said lip having an orifice 28 preferably of elongated slot form in which travels the arm 29 of the switch actuating device which arm works in the slot 5 of the base.

60 At the inner or lower end of this arm the actuator device operates the current controlling means and then extends in an aligned

relation to the right longitudinally of the base and is contained in the groove 4. It afterwards passes further to the right away from the base where the central or intermediate portion of the said actuator is bent 70 into the yoke-shaped arm 30 having two complementary adjacent side portions, and it then extends through the bearing formed by the slot 31 of the wall of the casing exterior of the latter where it terminates in the 75 exteriorly located handle 32.

It will be noted that the control members 13 and 18 are moved by a device 29 working below the same and are held a good distance apart by the insulating bar 26 thereby eliminating any danger of the current jumping from one to the other, or of any metallic material falling upon the same which might occur where the throw of the said control members is effected by an overhead actuating 80 means. The circuit opening and closing ends of the control members are always higher or at a greater distance from the base than is the end of the actuating arm 29, which latter works with an upward 90 movement in raising the said ends.

When the hinged control members 13 and 18 are in a live or operative closed circuit position the cover 3 cannot be closed for the reason that the parts are so relatively 95 arranged that a hook 33 carried by the cover will strike against the yoke-shaped arm 30.

In order to close the housing or casing therefore by the cover 3 and to lock the same in its closed relation it is first necessary to 100 open the control members 13 and 18 by manipulating the actuator handle 32 so that it will cause the actuator arm 29 to turn and carry the control members into their open or inoperative position.

105 The cover may now be closed and upon manipulating the actuator handle properly the hook 33 will be entered between and enclosed by the members of the yoke-shaped arm 30 thereby locking the cover to the housing and switching the control members or switch levers 13 and 18 into operative position and closing the circuits passing through the said housing, which thereafter 110 cannot be opened again without once more manipulating the actuator handle 32 and thereby disrupting the circuit at the control members. Otherwise the actuating means and cover are independently movable.

115 It therefore follows that in order to inspect the box or housing in order to ascertain the condition of the fuse elements of the circuit controlling members, the cover must first be unlocked thereby moving the circuit controlling members into an "off" or 120 circuit opening position. Any defective fuse elements may now be removed and renewed or replaced with safety, after which the cover may be closed and the actuating device moved so as to carry its connected switching 125 130

elements to the "on" or circuit closing position, whereby access will now be prevented to the live portions of the device.

The actuator handle 32 may be held in an additional locked relation by means of any suitable extraneous devices, as a padlock or other locking or sealing means to prevent surreptitious removal, or theft of current, or other tampering of the device.

10 I wish it to be understood that I do not desire to be limited to the particular use or the exact details of construction shown and described, for obvious modifications will occur to persons skilled in the art.

15 What I claim as my invention is:—

1. In a device of the class described, a base, a circuit controlling device, means to hold the same to the base, means to actuate the circuit controlling device, a longitudinal groove in said base in which a part of the actuating means works, and a transverse slot in the base in which another portion of the said actuating means works.

2. In a device of the class described, a base, a circuit controlling device, means to hold the same to the base, means to actuate the circuit controlling device, a longitudinal groove in said base in which a part of the actuating means works, and a transverse slot in the base in which another portion of the said actuating means works with a simultaneous movement.

3. In a device of the class described, a circuit controlling means, a base to support the same in a hinged relation, a housing therefor having a cover made with a locking means, and a unitary device having one bearing within the housing and adapted at one end to actuate the circuit controlling means and terminating at the other extremity in a handle exterior of the housing and having its other bearing in a wall of the latter and also having an intermediate central aligned portion being bent back upon itself to form

45 a loop to engage and become disengaged from the cover locking means at will, whereby when the handle is moved to one position the said actuating device will hold the circuit controlling means in an open relation and will be disengaged from the cover locking means to allow the cover to be opened, and when the cover is closed and the handle is moved to another position the actuating device will hold the circuit controlling means in a closed relation and will be engaged with the said cover locking means.

50 4. In a device of the class described, a circuit controlling means, a base to support the same in a hinged relation, a housing therefor having a cover made with a locking means, and a unitary device having one bearing within the housing in the base thereof and adapted at one end to actuate the circuit controlling means and terminating

5 at the other extremity in a handle exterior of the housing and having its other bearing in a wall of the latter and also having an intermediate central aligned portion formed with means to engage and become disengaged from the cover locking means at will, whereby when the handle is moved to one position the said actuating device will hold the circuit controlling means in an open relation and will be disengaged from the cover locking means to allow the cover to be opened, and when the cover is closed and the handle is moved to another position the actuating device will hold the circuit controlling means in a closed relation and will be engaged with the said cover locking means.

55 5. In a device of the class described, a circuit controlling means, a base to support the same in a hinged relation, a housing therefor having a cover made with a locking means, and a unitary device having one bearing within the housing and comprising a groove in the base of the latter, and adapted at one end to actuate the circuit controlling means and terminating at the other extremity in a handle exterior of the housing and having its other bearing in a wall of the latter and also having an intermediate central aligned portion formed with means to engage and become disengaged from the cover locking means at will, whereby when the handle is moved to one position the said actuating device will hold the circuit controlling means in an open relation and will be disengaged from the cover locking means to allow the cover to be opened, and when the cover is closed and the handle is moved to another position the actuating device will hold the circuit controlling means in a closed relation and will be engaged with the said cover locking means.

60 6. In a device of the class described, a circuit controlling means, a base to support the same in a hinged relation, a housing therefor having a cover made with a locking means, and a unitary device having one bearing within the housing and comprising a groove in the base of the latter, and adapted at one end to work in a slot in the base to actuate the circuit controlling means and terminating at the other extremity in a handle exterior of the housing and having its other bearing in a wall of the latter and also having an intermediate central aligned portion formed with means to engage and become disengaged from the cover locking means at will, whereby when the handle is moved to one position the said actuating device will hold the circuit controlling means in an open relation and will be disengaged from the cover locking means to allow the cover to be opened, and when the cover is closed and the handle is moved to another position the actuating device will

hold the circuit controlling means in a closed relation and will be engaged with the said cover locking means.

7. In a device of the class described, a base, a circuit controlling device, means to hold the same to the base, and means to actuate the circuit controlling device, a groove being made in the base forming a bearing in which the actuating means is adapted to work.

8. In a device of the class described, a circuit controlling means, a device to hold the same in a hinged relation, a housing therefor having a cover provided with a hook, a device to actuate the circuit controlling means comprising a rod with a bearing at one end within the housing and another bearing in a wall of the latter and having an intermediate aligned yoke-shaped means to engage the hook of the cover, the said rod terminating in a handle exterior of the housing whereby the said actuating device may be moved.

9. In a device of the class described, a housing with a cover having a hook, a groove in the base of the housing, a dual circuit controlling means, an insulating bar to hold opposite parts of the same spaced from each other, and a device to actuate the insulating bar to move the circuit controlling means and working below the same, said actuating device having one bearing in the groove and another bearing in a wall of the housing and an intermediate yoke-shaped portion to engage the hook and terminating in a handle exterior of the housing.

10. In a device of the class described, a hinged circuit controlling means, a housing therefor having a base made with a groove and a cover provided with a hook,

a device to actuate the circuit controlling means comprising an arm to raise and lower the circuit controlling means and a yoke-shaped portion to rise and fall simultaneously with respect to the hook of the cover, and also terminating in a handle exterior of the housing whereby the actuating device may be moved, the latter having one bearing in the groove and another bearing in a wall of the housing.

11. In a device of the class described, a circuit controlling means, a base to support the same in a hinged relation, a housing therefor having a cover made with a locking means, and a unitary device having one bearing within the housing and comprising a longitudinal groove in the base of the latter, and adapted at one end to work in a transverse slot in the base to actuate the circuit controlling means and terminating at the other extremity in a handle exterior of the housing and having its other bearing in a wall of the latter and also having an intermediate central aligned portion formed with means to engage and become disengaged from the cover locking means at will, whereby when the handle is moved to one position the said actuating device will hold the circuit controlling means in an open relation and will be disengaged from the cover locking means to allow the cover to be opened, and when the cover is closed and the handle is moved to another position the actuating device will hold the circuit controlling means in a closed relation and will be engaged with the said cover locking means.

Signed at Brooklyn in the county of Kings and State of New York this 23rd day of May A. D. 1924.

BENJAMIN C. KING.
